PANORAMIC RECEIVER WITH UNWANTED SIGNAL REJECTOR

Raymond F. Hollandbeck, Pittsburgh, Pa., assignor to Westinghouse Electric Corporation, East Pittsburgh, Pa., a corporation of Pennsylvania

Application December 30, 1952, Serial No. 328,681

6 Claims. (Cl. 250—20)

This invention relates to radio systems, and more particularly to frequency selective control circuits therefor.

It is an object of this invention to provide an improved frequency selective control system.

It is another object to provide an improved frequency selective control system for a frequency sweeping search receiver that is independent of the strength of the incoming signal.

It is another object to provide an improved frequency selective control system that is capable of varying the sensitivity of a controlled circuit over a predetermined frequency interval which may be automatically shifted in the frequency spectrum in response to an independent variable.

Still another object of this invention is to provide an improved frequency selective system to vary the sensitivity of the controlled circuit over a frequency interval in which the frequency interval may be easily varied.

These and other objects are effected by my invention as will be apparent from the following description and claims taken in accordance with the accompanying drawing throughout which like reference characters indicate like parts and in which:

Figure 1 is a schematic drawing of a preferred embodiment of my invention, and

Fig. 2 comprises a curve illustrating the response of the frequency selective control system.

Fig. 1 illustrates a conventional superheterodyne circuit comprising an antenna 3 for receiving incoming signals, a radio frequency amplifier 4, a mixer 19, a plurality of intermediate amplifier stages 5 and 6, a second detector 7 and a final amplifier 8.

Referring in detail to Fig. 1, there is shown a sawtooth generator 11 comprising a neon tube 21 with one electrode connected to ground and the other electrode connected through a resistor 20 to a suitable power supply 18 illustrated as a battery. A condenser 22 is connected across the two electrodes of the neon tube 21. The ungrounded electrode of the neon tube 21 is connected through an isolating resistor 23 to a reactance tube circuit 12.

The reactance tube circuit 12 is comprised of a triode vacuum tube 25 having a plate electrode 28, a grid electrode 27 and a cathode electrode 26. The plate electrode 28 is connected through an impedance 35 to the power supply 18. The output of the sawtooth generator 11 is connected through the resistor 23 to the grid electrode 27, while the cathode electrode 26 is connected through a parallel combination of resistor 33 and condenser 32 to ground. A resistor 29 and blocking condenser 34 are connected in series between the plate electrode 28 and the grid electrode 27 of the tube 25. A parallel combination of a resistor 30 and a condenser 31 are connected from the grid electrode 27 of the tube 25 to ground.

A conventional oscillator circuit 13 comprising a triode vacuum tube 37 having a plate electrode 38, a grid electrode 39 and a cathode 40 is connected to the re-

actance tube circuit 12. A tuned circuit comprising condenser 42 and inductor 41 in parallel is connected between the grid electrode 39 and ground. A grid leak resistor 43 and a condenser 45 connected in parallel 5 connect the tuned circuit comprising inductor 41 and capacitance 42 to the grid electrode 39. The cathode 40 is connected to the tap 44 of the inductor 41, while the plate electrode 38 is connected to the power supply 18. The plate electrode 28 of the reactance tube 25 is connected to the tuned circuit comprising the inductance 41 and the capacitance 42 by means of a blocking condenser 36. The ungrounded terminal of the tuned circuit comprising the inductance 41 and capacitance 42 is connected through a resistor 46 to a band pass filter 14.

The filter 14 comprises a condenser 47 connected in

series with the combination of a condenser 48 and an inductor 49 in parallel between the resistor 46 and ground.

The output of the band pass filter 14 taken at a point 20 between the condenser 47 and the parallel connected condenser 48 and inductor 49 is connected through a coupling condenser 50 to a reactance tube filter shifter 15. The reactance tube filter shifter 15 is of similar design to the reactance tube circuit 12. The reactance 25 tube filter shifter 15 comprises a triode vacuum tube 54 having a plate electrode 51, a grid electrode 52 and a cathode electrode 53. The cathode 53 is connected to ground through a parallel combination of resistor 61 and a condenser 60. The plate electrode 51 is connected 30 through a resistor 62 to the power supply 18. A series combination of a condenser 55 and a resistor 56 is connected between the plate electrode 51 and the grid electrode 52, while a parallel combination of a resistor 57 and a condenser 58 is connected between the grid electrode 52 and ground. A control voltage from any suitable source for the reactance tube filter shifter 15 may be connected to the terminal 59. A detector circuit 16 comprising a diode vacuum tube 65 is connected across the plate and cathode circuits of the reactance tube 54.

40 A coupling condenser 63 connects the plate electrode 51 of the tube 54 to the cathode 66 of the diode rectifier 65. The cathode 66 of the diode 65 is connected through an inductor 68 to ground. The plate electrode 67 of the diode 65 is connected to ground through a condenser 69, and a series combination of resistors 70 and 45 71 connected in parallel with respect to the condenser 69. The common terminal of the resistors 70 and 71 is connected through a variable resistor 73 to the power supply 18.

The plate electrode 67 of the diode 65 is also connected 50 by means of a conductor 72 to a switching means 17. The switching means 17 comprises a triode vacuum tube 76 having a plate electrode 77, a grid electrode 78 and a cathode 79. The conductor 72 is connected to the grid electrode 78, while the plate electrode 77 is connected through a relay coil 80 to the power supply 18.

The cathode 79 is connected to ground. The relay 81 comprises a coil 80, contacts 83 and closing bar 84. The relay 81 in the closed position will supply the plate voltage to the intermediate frequency amplifier 5 by conductor 82 from the power supply 18. It is obvious that a control voltage may be supplied to any stage or stages and to any control element by relay 81.

In the operation of the circuit, an incoming signal, from any suitable source, is fed into the mixer 19 by 65 means of the antenna 3 and radio frequency amplifier 4. The mixer 19 combines the incoming signal with the signal from the local oscillator 13. The signal from the local oscillator 13 differs in frequency from that of the incoming signal by a specified amount, namely the intermediate frequency. The output of the mixer 19 is fed to the intermediate frequency amplifier 5.

The frequency range of the incoming signal is scanned or searched by the described system by means of sweeping the local oscillator 13 over a selected range of frequencies below the range of frequencies of the incoming signal. The sweeping action of the local oscillator 13 is accomplished by the sawtooth generator 11 and the reactance tube circuit 12.

If a certain frequency interval within the range of the incoming signal is undesired in the output of the described system, my invention allows the rejection of this undesired frequency interval. My invention permits a control system that is absolute in action and the frequency interval of rejection is held constant regardless of the level of the incoming signal.

The filter 14 is a frequency sensitive network of simple and inexpensive design. Its action is to pass or reject frequencies between certain frequency limits. In my specific example, I utilize a band-pass type filter. This network may be a relatively simple filter such as one made of inductance 49 and capacitances 47 and 48. The response curve of a typical filter is shown in Fig. 2 where I have plotted the output voltage of rectifier 16 versus frequency. The filter 14 is peaked or tuned to the center of a frequency interval of the local oscillator 13 differing from the undesired frequency interval of the incoming signal by an amount equal to the intermediate frequency.

The center frequency 90 of the filter 14 may be shifted automatically over a small range of frequencies near the original center frequency if desired. This may be accomplished by the reactance tube filter shifter 15. The application of a voltage on the terminal 59 from an independent source to the frequency shifter 15 will shift the center frequency of the filter 14 as desired.

The output of the filter 14 is fed into the rectifier or detector circuit 16 in order to provide a direct current whose magnitude is dependent on the response of the filter 14. A bias voltage is supplied to the rectifier circuit 16 from the power supply 18 through the variable resistance 73 and is added to the output of the rectifier 16 to set or determine the frequency interval width 91. The center frequency 90 remains constant and the width of the frequency interval 91 may be varied by merely adjusting the variable resistor 73, which raises or lowers the response curve in Fig. 2. The output voltage derived from the detector 16 and the bias voltage is of sufficient magnitude to operate the switching stage 17. The voltage required to operate the switching stage 17 is indicated by the line 92 on Fig. 2. The rectifier voltage supplied to the grid 78 of the vacuum tube 76 will allow the tube 76 to conduct causing the relay 81 to open which will remove the plate supply voltage 18 from the intermediate frequency amplifier 5, and desensitize the system.

The switching stage 17 may be omitted from the control circuit if the response desired need not be too rapid. However, if a more absolute or abrupt action is desired, the switching circuit 17 is utilized.

The switching stage 17 is utilized to supply a voltage to one or more of the stages of the receiving system, such as the amplifier stages, to alter its sensitivity. The filter 14 is designed to pass the difference frequency interval that corresponds to the undesired frequency interval in the incoming signal.

It is also obvious to those skilled in the art that a filter network of the band-rejection type may be utilized in the same application as the band-pass type, except that the rectifier diode must be connected in an appropriate manner. A band-rejection filter may easily be constructed of infinitesimal band width.

While I have shown my invention in only one form, it will be obvious to those skilled in the art that it is not so limited, but is susceptible of various changes and modifications without departing from the spirit and scope thereof.

I claim as my invention:

1. In a radio apparatus, a generator, a first reactance

tube circuit driven by said generator, an oscillator having a tuned circuit, means connecting said reactance tube circuit across the tuned circuit of said oscillator, a tuned filter circuit connected across the output of said oscillator, a second reactance tube circuit connected to said filter circuit for varying the tuning of said filter circuit, a detector connected across the output of said filter circuit for rectifying the potential appearing across said filter circuit, a variable bias control connected to said detector circuit, switching means, and means connecting the output of said detector to said switching means for desensitizing said apparatus within a predetermined frequency interval.

2. A frequency selective control system for radio apparatus comprising a local oscillator, a frequency sensitive circuit, a reactance tube circuit connected to said frequency sensitive circuit for varying the frequency of sensitivity of said frequency sensitive circuit, a rectifier circuit connected to the output of said frequency sensitive circuit, and means of coupling the output of said rectifier to a stage of said radio apparatus for desensitizing said radio apparatus within a predetermined frequency interval.

3. Radio apparatus comprising a mixer circuit having an input for incoming radio frequency signals, a local oscillator controlled by a sweep generator adapted for scanning over a selected range of frequencies below that of the range of frequencies over which the incoming signals are anticipated, said local oscillator and incoming signals being connected to said mixer circuit, a control circuit including a filter connected to said local oscillator, a rectifying means connected to the output of said filter, a filter shifter connected to said filter and controlled by an independent variable, a switching circuit connected to the output of said rectifier for altering the sensitivity of said radio apparatus within a predetermined frequency interval determined by said filter.

4. In combination, radio apparatus comprising a local oscillator, means for controlling said local oscillator by a sweep generator adapted for scanning over a selected range of frequencies below a range of frequencies over which the incoming signals are anticipated, a control circuit comprising a filter connected to the output of said local oscillator, rectifying means connected to the output of said filter, means for adding a steady direct bias voltage to said rectifier to determine a selected range of frequencies over which the rectifier operates, and means for applying the output from said rectifier to alter the sensitivity of said radio apparatus to said incoming signals within a predetermined frequency interval.

5. A frequency sensitive circuit which is non-responsive over a predetermined frequency interval within a frequency band comprising in combination a local oscillator, a mixer circuit to which a control signal and the output of said local oscillator are supplied, a sweep generator coupled to said local oscillator for scanning over a selected range of frequencies below that range of frequencies over which the incoming signal is anticipated, a frequency selective control circuit including a filter connected to the output of said local oscillator, a rectifying means connected to the output of said filter, a steady direct-current bias voltage added to said rectifier output, and a switching means connecting said bias voltage and output of said filter to alter the sensitivity of said circuit within a predetermined frequency interval.

6. In combination, radio apparatus comprising a mixer circuit, an intermediate frequency amplifying means, a local oscillator controlled by a sweep generator adapted for scanning over a selected range of frequencies within a band of anticipated incoming signals, means connecting said incoming signals and said local oscillator to said mixer circuit and means for coupling the output of said mixer circuit to said intermediate frequency amplifying means, a control circuit comprising a filter coupled to

the output of said local oscillator, a rectifying means connected to the output of said filter, a steady direct bias voltage added to said rectifier output to determine the range of frequencies over which the output from said rectifier is utilized, a switching circuit, means for connecting the output of said rectifier to said switching circuit, said switching circuit having its output coupled to a stage of said radio apparatus to alter the sensitivity of said radio apparatus to said incoming signals within a predetermined frequency interval.
